UNITED STATES PATENT OFFICE

ALVIN L. ABRAHAMSON, OF MACKSVILLE, KANSAS

WRENCH

Application filed June 12, 1929. Serial No. 370,351.

This invention pertains to improvements in wrenches and the like and has as its primary object the provision of a wrench of the quick acting type consisting of but very few parts, very simple in construction and can be conveniently and economically manufactured, durable, easily operated, and otherwise well adapted for the purpose intended.

Another very important object of the invention is to provide a novel wrench wherein there is a movable jaw shiftable toward a fixed jaw by means of a handle having a detachable engagement with the movable jaw.

Other objects and advantages of the invention will appear from the study of the following description taken in connection with the accompanying drawings, wherein:

Figure 1 is a side elevation of a wrench constructed in accordance with the present invention and showing certain parts broken away.

Figure 2 is an end elevation of the invention.

Figure 3 is a side elevation of the stationary jaw.

Figure 4 is a fragmentary detail sectional view taken through the wrench and showing the spring means for holding the operating lever in adjusted position.

Figure 5 is a side elevation of the movable jaw.

With reference more in detail to the drawings it will be seen that the main body or head 5 is provided with a stationary jaw 6 and with two spaced parallel walls 7-7, which are provided internally with opposed transversely extending channels or grooves 8-8. As clearly illustrated, the stationary jaw 6 is at one side of the member 5 and the two parallel walls 7-7 extend laterally therefrom.

The movable jaw 9 comprises a head 10, formed on one end of a body portion 11 and is provided on opposite faces with a rib 12-12 adapted to be received within the channels of the head 5 when the body portion 11 thereof is arranged for sliding movement between the walls 7-7 of the stationary jaw.

As is clearly illustrated, the body portion 11 of the movable jaw 9 has a recess 12'

formed thereon, for a purpose to be herein-after more fully set forth.

The handle bar lever for operating the movable jaw 9 is of a construction best illustrated in Figure 1 and comprises a body portion 13, which body portion tapers toward one end and terminates in a rounded extremity or head 14 adapted to be received within the recess 12' of the movable jaw. The lever adjacent the rounded head 14 is provided with a bolt and nut 15 and 16 respectively, adapted to constitute a fulcrum such as is illustrated in Figure 1. The nut and bolt is adapted to extend through registering slots 17-17 formed in the two side walls 7-7 as 65 illustrated.

As shown each of these slots 17 is provided with notches 18 each of the slots being provided also with a projection 17' separating the notches, and disposed at right angles to the length of slots 17. It is also to be noted that projection 17' between the notches 18 is rounded on one edge as at 19 and formed on its opposite edge so as to provide a recess 20.

From the foregoing then, it will be seen that the bolt 15 extends through the slot 17-17 to rest in either of the notches 18, and is adapted to travel in the slot from one notch to the other to assume different positions as is apparent.

Thus it will be seen that when the lever is pushed upwardly between the walls 7-7, the rounded head 14 of the lever will engage with the recess 12' formed in the body portion of the movable jaw 9 and as the bolt 15 rides over the rounded head 19 of the projections 17' between the notches 18, the movable jaw 10 will be moved toward the stationary jaw 6, so as to grip an object between the two jaws 90 and at the same time permit the bolt to drop down into the other of the notches 18 and it is obvious that further pressure being applied to the handle to turn the bolt 15 in the last mentioned position will urge the movable jaw against the member to be held between the jaws thus effecting a tight grip of the jaws upon the member to be held.

Attention is now directed to Figure 4, wherein it is illustrated that the body por-

tion 13 of an operating lever has a slot 19' formed on one face thereof, which slot is adapted to accommodate a suitable spring member 20', one end of said spring member 5 being anchored within the slot as at 21, and as illustrated this spring is adapted to bear against one of the side walls 7 to hold the lever in an adjusted position.

As shown in Figure 5, the movable jaw, 10 now designated by the reference character 22 is provided with the usual body portion 24, which body portion is similar to the body portion 11 of the first mentioned movable jaw, and the jaw portion 25, which jaw portion 15 25 is formed on its inner face with teeth 26. A jaw so formed as just described is preferably to be used when the wrench is to be used as a pipe wrench, whereas it may be preferable to use the first mentioned type 20 of jaw as an ordinary wrench for holding objects with square sides, but of course the adjusting positive grip action will act as well when either jaw is used.

From the foregoing then, it will be seen 25 that I have provided an improved wrench capable of varied use, which is very simple in construction and which will be found thoroughly efficient and reliable in use.

Even though I have herein shown and de- 30 scribed certain detail structural features of my invention, it is to be understood that the same is susceptible to changes fully comprehended by the spirit of the invention as herein described and the scope of the appended 35 claim.

What is claimed is:

In a wrench structure of the character de- 30 scribed, a fixed jaw having a pair of spaced parallel walls fixed thereto and extending lat- 40 erally therefrom, a movable jaw slidably mounted on the upper edges of said wall for movement toward or away from said fixed jaw, said movable jaw having a body portion extending between said parallel walls, said 45 body portion of said movable jaw having a rounded recess formed therein, each of said parallel walls having a slot formed therein, said slots being in alinement, each of said walls being provided with a projection dis- 50 posed at right angles to the length of said slots, said projections being respectively pro- 55 vided with a rounded edge, a lever rockably mounted in said side walls and having a rounded extremity adapted to be received in 60 the recess of the body portion of said movable jaw, a bolt for said lever having its opposite ends extending into said slots and 65 ridable over the rounded edges of said projection, upon movement longitudinally with respect to the slots whereby when said bolt is 70 moved over the rounded edges of said projections said rounded extremities of the lever will be moved into the recess of the body of 75 said movable jaw for moving the latter toward 80 or away from said stationary jaw, said lever 85 having a recess formed therein, a spring an- 90 chored in said recess and having an intermediate portion thereof frictionally engaging one of said parallel walls for retaining said lever against casual displacement.

In testimony whereof, I affix my signature. 70

ALVIN L. ABRAHAMSON.
